INTERNAL-COMBUSTION ENGINE

Guy Davies, Kempston, England

Application June 19, 1944, Serial No. 540,936
In Great Britain September 8, 1943

5 Claims. (Cl. 123—57)

This invention relates to internal combustion engines and more particularly to multi-cylinder engines.

According to the present invention a multi-cylinder internal combustion engine comprises a plurality of axially arranged engine cylinders each having a piston reciprocating therein, all the pistons being connected together for reciprocal movement as a unit for driving the engine crank shaft. The engine may comprise one or more sets of four axially arranged cylinders, the pistons of each set being connected together by a link which transmits the reciprocal movement of the piston unit to the crank journal of the engine crank shaft.

To enable the invention to be fully understood it will now be described with reference to the accompanying drawing wherein

Fig. 1 is a longitudinal section of an engine according to one form of the invention,

Fig. 2 is a fragmentary sectional plan view showing the link connecting the piston rods and the bearing for connecting the piston unit to a power shaft, the engine cylinder being omitted for the sake of clarity, and

Fig. 3 is a section on the line 3—3 of Fig. 1.

As shown in the accompanying drawing the engine casing is formed by end castings 1, 2 attached by walls 3, 4 to the engine crank case, and a central casting 5 also attached to the crank case. The castings are spaced apart axially and the spaces between them outside the crank case are covered by plates 6, 7. The castings 1 and 2 comprise cylinders for pistons 8 and 11 and the casting 5 comprises cylinders for pistons 9 and 10. The pistons 8 and 9 are connected by a rod 12 and the pistons 10 and 11 by a rod 13. A rotary sleeve valve 14 is rotatably mounted between the cylinder walls and the pistons and is provided with a gear 15 mounted in ball bearings and adapted to be rotated by suitable gearing (not shown) driven from the main shaft of the engine.

The inner surface of the outer ends of the sleeve valve 14 have an annular recess to receive the skirt 16 of head members having walls 17, 18 forming housings for slidable piston-like members 19. The members 19 are urged to engage the cylinder wall by a spring or springs 20 and are each formed with a passage 21 adapted to register, as the sleeve 14 is rotated, with inlet and outlet ports, such as 22, and a sparking plug or injector opening 23, circumferentially spaced in the cylinder wall adjacent to the slidable members. The sleeve 14 is formed with walls 24, 25 and 26, 27 which form

6   housings for slidable members 28 and 29. The construction and function of the slidable members 19, 28 and 29 are fully described in our co-pending application Serial No. 540,935, filed June 19, 1944, and further description is not considered necessary. The head members are formed with hollow chambers 30, 31 and a further hollow chamber 32 is provided between the slidable members 28, 29 at the intermediate part of the sleeve 14. Oil for cooling and lubricating is injected into these chambers 30, 31 and 32 by pipes 33, 34, 35, a controlled part of this oil flowing between the walls of the sleeve and the cylinder through suitable conduits or grooves (not shown).

10   15   The oil is circulated through chambers 30, 31 and 32 back to the engine sump.

15   20   The piston rods 12, 13 are connected together for movement as a unit by a link 36 the ends of which are secured to the centre of the rods by pins 37, 38. The link 36 is slidably mounted in a recess in the outer wall of the sleeve 14, the wall being slotted at 39, 40 to permit the oscillation of the pins and link. The pin 38 is secured to an annular member 41 having castellations 42 which cooperate with castellations 43 of a cooperating annular member 44. Sufficient play is provided between the castellations 42, 43 to allow free relative rotation. The member 44 is held around the sleeve 14 by a bolt 45 and is pivotally connected to a connecting rod 46 which is coupled with a crank journal 47 of the main drive shaft of the engine.

20   25   In operation the gear 15 is rotated to rotate the sleeve 14 and the combustion spaces of the cylinders are connected through the slidable members in timed sequence with the ports in the cylinders and supplied with combustible mixture which is compressed, ignited and subsequently exhausted. The timing of the four cylinders is so arranged that all pistons are always travelling in the same direction and by means of the link 36 the reciprocation of the piston is transmitted through the thrust bearing members 41, 44 to the connecting rod 46 and crank journal of the engine crank shaft.

25   30   If desired further sets of four cylinders similar to that shown and described may be arranged side by side, the pistons of each set being coupled for movement as a unit and connected by a connecting rod with separate crank journals for driving a common main drive shaft. Any number of sets may be provided for example 12 sets would provide a 48 cylinder engine.

30   35   When several sets of cylinders are provided two sets of pistons may be connected to a single crank

journal, if desired, by arranging for one of the connecting rods to have a forked end.

To reduce the overall dimensions of the engine the end castings 1 and 2 may be adapted to receive slidable members such as described in Figs. 4 to 7 of our co-pending application No. 13,847 of 1943.

I claim:

1. In a four-stroke cycle internal combustion engine, two pairs of open-ended diametrically opposed cylinders, a piston reciprocating in each of said cylinders, a connecting rod rigidly connecting the two pistons in each pair of opposed cylinders, a link extending axially of the cylinders and rigidly connected at each end with a connecting rod of a pair of pistons, a power shaft, and means for connecting one of said connecting rods with said power shaft.

2. In a four-stroke cycle internal combustion engine, two pairs of open-ended diametrically opposed cylinders, a piston reciprocating in each of said cylinders, a connecting rod rigidly connecting the two pistons in each pair of opposed cylinders, a link extending axially of the cylinders and rigidly connected at each end with a connecting rod of a pair of pistons, a crankshaft and a crank rod connecting one of said connecting rods with said crankshaft.

3. In a four-stroke cycle internal combustion engine, two pairs of open-ended diametrically opposed cylinders, a piston reciprocating in each of said cylinders, connecting rods rigidly connecting the two pistons in each pair of opposed cylinders, a sleeve valve rotatably mounted between the inner wall of the cylinders and the pistons, a link extending axially of the cylinders and slidably mounted in a recess in the sleeve valve, means at

each end of the link engaging one of the connecting rods, a power shaft and means for drivingly connecting one of said connecting rods with said power shaft.

4. In a four-stroke cycle internal combustion engine, two pairs of open-ended diametrically opposed cylinders, a piston reciprocating in each of said cylinders, connecting rods rigidly connecting the two pistons in each pair of opposed cylinders, a sleeve valve rotatably mounted between the inner wall of the cylinders and the pistons, a link extending axially of the cylinders and slidably mounted in a recess in the sleeve valve, means at each end of the link engaging one of the connecting rods, means converting the combined rotary and reciprocating motion of the connecting rods into simple reciprocating motion, a crank shaft and a crank rod connecting the said crank shaft with said means.

5. In a four-stroke cycle internal combustion engine, two pairs of open-ended diametrically opposed cylinders, a piston reciprocating in each of said cylinders, connecting rods rigidly connecting the two pistons in each pair of opposed cylinders, a sleeve valve rotatably mounted between the inner wall of the cylinders and the pistons, a link extending axially of the cylinders and slidably mounted in a recess in the sleeve valve, means at each end of the link engaging one of the connecting rods, two relatively rotatable members connected for reciprocation as a unit, a crank shaft and a crank rod connected with the crank shaft and one of said members, and means connecting the other of said members to one of the connecting rods of the pairs of opposed pistons.

GUY DAVIES.
